UNITED STATES PATENT OFFICE.

WILLIAM C. MEYER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WAX-THREAD SEWING MACHINE.

1,409,193.

Specification of Letters Patent. Patented Mar. 14, 1922.

Application filed April 28, 1917. Serial No. 165,107.

To all whom it may concern:

Be it known that I, WILLIAM C. MEYER, a citizen of the United States, residing at Beverly, in the county of Essex and State of Massachusetts, have invented certain new and useful Improvements in Wax-Thread Sewing Machines; and I do hereby declare the following to be a full, clear, and exact description of the invention, such as will enable others skilled in the art to which it appertains to make and use the same.

This invention relates to wax-thread sewing machines, and more particularly to machines for sewing inseams of shoes.

15 The invention is illustrated in this application as embodied in a machine for sewing uppers to the soles of turned shoes. The invention is not limited, however, to this particular type of machine, but may be embodied with advantage in machines for sewing welts and uppers to the insoles of welted shoes.

20 The primary object of the invention is to improve the construction and mode of operation of various parts of inseam shoe sewing machines, with the view of increasing the efficiency and reliability of such machines.

25 With this and other objects in view, the features of the invention consist of the novel and improved constructions, arrangements and combinations of parts hereinafter described and particularly pointed out in the claims.

30 The invention will be readily understood from the accompanying drawings illustrating a machine embodying the invention in its preferred form, and the following detailed description of the constructions 35 therein shown.

35 In the drawings, Figure 1 is a view in side elevation illustrating the head of a turned shoe sewing machine embodying the invention;

40 Fig. 2 is an enlarged view in side elevation illustrating a portion of the head of the machine, with certain parts of the frame removed to show more clearly the structure;

45 Fig. 3 is a detail view in side elevation illustrating particularly the back gage and back rest mechanisms;

50 Fig. 4 is a view in horizontal section of the mechanism illustrated in Fig. 3;

Fig. 5 is a detail sectional view taken substantially on the line 5—5 of Fig. 3;

Fig. 6 is a detail sectional view taken substantially on the line 6—6 of Fig. 5;

Fig. 7 is a detail sectional view taken substantially on the line 7—7 of Fig. 5;

And Fig. 8 is a detail view in side elevation illustrating particularly the back rest mechanism;

The machine illustrated in the drawings is constructed and arranged for sewing uppers to the soles of turned shoes. The machine comprises an oscillating curved hook needle 2 arranged to enter the between substance of the sole upon the outer or marginal side thereof, a feed point or awl 4, 65 a looper 6, a thread arm 8, and a tension device 10, having substantially the same construction, arrangement and mode of operation as the corresponding parts of the machine illustrated and described in applicant's pending application Serial No. 95,893, filed May 6, 1916. The channel guide 11 of the machine illustrated in the drawings differs from the channel guide of the machine illustrated in the above application in 70 that it is provided with a lip or finger 12 extending rearwardly from the body of the channel guide and laterally in the direction of feed for engaging the upper side of the channel flap to prevent the channel flap from 75 being raised by the pull exerted on the thread by the thread arm during the loop drawing stroke of the thread arm. The channel 80 guide construction is illustrated and described in applicant's pending application, 75 Serial No. 69,880, filed January 3, 1916 upon which Patent No. 1,259,765, dated March 19, 1918, was granted. The arrangement and mode of operation of the channel 85 guide are substantially the same as in the machine illustrated and described in application Serial No. 95,893 referred to above. The machine illustrated in the drawings is also provided with a take-up 90 13, a back gage 14 and a back rest 15.

The awl 4 of the machine is clamped to the awl carrier 16, which is pivotally mounted upon a stud 18 projecting laterally from a block 20 secured to the lower end of the laterally movable feed member or lever 22 105 mounted on the stud 24. The awl carrier 16 is connected by a link 26 (Fig. 2) with one arm of a bell crank lever 28 pivoted

upon the stud 30. The other arm of this bell crank is connected by a link 32 with the forward end of a cam actuated lever 34 pivoted upon a stud 36, and carrying a cam roll 37 engaging in a cam groove in a cam disk mounted on the main shaft 38 of the machine. The link 26 is connected at its respective ends with the awl carrier 16 and with the bell crank lever 28 by universal joints to accommodate the movements of the awl carrier in the direction of feed.

The channel guide 11 also is secured to the lower end of the feed member or lever 22. The feed member or lever 22 has a reciprocating movement longitudinally of the stud 24 to carry the awl and channel guide back and forth in the direction of feed, and a slight pivotal movement on the stud to engage the channel guide with and to disengage it from the bottom of the channel. The reciprocating movement of the feed member 22 upon the stud is imparted by means of an actuating lever 39 pivoted upon a stud 40, and having an arm 42 which carries a pin 44 engaging in a groove in a projection 46 on the feed member 22. The lever 39 has a second arm 48 carrying a cam roll 50 engaging in a cam groove in a cam disk mounted on the main shaft 38.

30 The heating devices for the machine are arranged to heat the machine by steam and are so constructed as to heat the frame at the point where the stud 24 is attached thereto to a relatively high temperature.

35 The heat transmitted in this manner, however, is not sufficient to heat the channel guide and awl to a high temperature, so that wax will not stick to these parts and accumulate thereon. As a further provision for 40 heating the member 22, a block 76 is mounted upon the parallel pipe sections 70 and 74, and is formed with a concavely curved contact face 78 for engagement with a complementary contact face formed upon a block 82 secured upon the forwardly projecting arm 45 on the feeding member 22. The contact faces of the heating block 76 and the block 82 are curved in an arc struck from the axis of the stud 24. With this construction a 50 comparatively large area of contact is maintained between the heating block 76 and block 82 during the reciprocating movement of the member 22 on the stud 24, and during the pivotal movement of said member on the 55 stud, the contact faces of the blocks sliding over each other during these movements of the feeding member. The heat transmitted from the block 76 to the feeding member 22 is sufficient to keep the channel guide 60 and awl heated to a high temperature. The heating devices briefly described above are fully illustrated and described in applicant's pending application Serial No. 352,585, filed January 19, 1920, which constitutes a division of the present application.

The take-up consists of a roll 103 mounted upon the forward end of an arm 104 carried by a lever 106 pivoted upon the stud 108. The lever 106 is actuated from a cam lever 110 (Fig. 2) pivoted upon the stud 112, the 70 arm 114 of which has a block and slot connection with the rear end of the lever 106. The other arm 116 of the cam lever carries a cam roll 118 engaging in a cam groove in a cam disk mounted upon the main shaft 38. 75 The arm 104 is pivoted upon a stud 120 carried at the forward end of the lever 106, and is acted upon by a coiled spring 124 which tends to swing the arm upwardly relatively to the lever. A locking arm 142 is provided 80 for locking the arm 104 to the lever 106. The locking arm 142 is adjustably mounted and is arranged so that when located in one position the arm 104 will be locked rigidly to the lever 106 and that when located in another position, the arm 104 can swing 85 relatively to the lever 106 in opposition to the tension exerted by the spring 124. This take-up mechanism is fully illustrated and described in an application, Ser. No. 252,970, 90 filed Sept. 6, 1918, which constitutes a division of the present application.

The back gage is arranged in the usual manner to engage the shoe close to the path of the needle so as to form a support for 95 the shoe. The back gage has substantially the same mode of operation as the welt guide of the machine disclosed in applicant's pending application, Serial No. 95,893 referred to above. That is, the back gage is 100 locked in forward position against forward or rearward movement during the greater part of each cycle of operations, including the time during which the needle is retracting from the work, is retracted out of engagement with the shoe during the feeding of the shoe, and is then moved forward yieldingly into contact with the shoe. The back gage is locked against rearward movement so that it will firmly support the shoe, particularly against the backward pull of 105 the needle as the needle retracts from the work. The locking of the back gage against forward movement prevents the back gage from advancing and displacing the shoe as 110 the channel guide is actuated to disengage its acting end from the bottom of the channel.

The back gage 14 is secured to the forward end of a lever 162 pivoted by means of a stud 164 to the forward end of the back gage slide or controller bar 166. The bar 166 is mounted for forward and rearward movement to carry the back gage into and out of engagement with the shoe, and the back gage is pivoted upon the stud 164 so that it can be oscillated to cause the back gage to move in a curved path which is practically concentric with the path of the needle during its forward and rearward 125 movement.

movements. This ensures that the back gage will always be located in the same position relative to the needle or to the path of the needle regardless of the thickness of the work. The rear end of the lever 162 carries a cam roll 168 engaging in a cam groove 170 in a cam plate 172 secured to the frame of the machine. The shape of the cam groove 170 is such that as the back gage is moved 5 forwardly and rearwardly it is oscillated on the stud 164 to cause it to move in a path substantially concentric with the path of the needle. The forward end of the bar 166 is supported by a swinging arm 174 pivoted at 10 its lower end upon a stud 176, the forked upper end of which embraces the bar 166 and carrier 162, and is pivotally connected to said bar and carrier by the stud 164. The rear end of the bar 166 passes through and 15 is supported by a block 178 pivotally mounted upon the lower arm of the cam lever 180 pivoted upon the stud 182. As shown particularly in Fig. 5, the block 178 is formed with oppositely extending bearing projections or trunnions 184 which engage in suitable bearings in the lever 180. For convenience in assembling the lever and the block, the lever is formed in two parts, indicated at 186 and 188 in Fig. 5. The part 20 188 of the lever is formed with a boss 189 fitting in an opening in the part 186, and the parts are secured together by the bolt 190, and held from relative displacement by the pin 192. The bar 166 is advanced and re- 25 tracted to move the back gage into and out of engagement with the shoe, and is locked in advanced position against forward and rearward movement during each cycle of operations. The bar is freely movable through 30 the block 178. The bar is advanced to bring the back gage into engagement with the shoe by means of a spring 194, the out-turned end of the arm 196 of which engages in a socket in the rear end of the bar. The rel- 35 ative movement of the bar and the block 178 is limited by means of a pin 198 threaded into the block and having its inner end projecting into a slot in the bar.

The bar is locked in advanced position 40 against retracting movement by means of a roll clutch comprising a clutch box 202 formed on a bracket 204 secured by a bolt 206 to the frame of the machine. In the clutch box 202 are mounted clutch rolls 208 45 arranged upon opposite sides of the bar 166 to engage flat faces formed upon the bar. The forward end of the block 178 is arranged to enter between the two sides of the clutch box 202, and is formed with inclined 50 faces 210 for engagement with the clutch rolls 208 to force the rolls against the bar 166. The clutch rolls fit somewhat loosely in the clutch box, so that when the block 178 is disengaged from the rolls, the bar 55 166 will move freely between the rolls.

When the block 178 is moved forwardly to bring the inclined faces 210 on the block into engagement with the clutch rolls 208, the rolls are forced against the bar 166 to clutch the bar and lock it against rearward movement between the rolls. The mechanism for retracting the bar comprises a second roll clutch which is also utilized to lock the rod in advanced position against forward movement. This roll clutch comprises a clutch box 212 mounted to slide longitudinally upon the bar 166 and clutch rolls 214 mounted in the box upon opposite sides of the bar and arranged to engage flat surfaces formed on the bar. The rear 70 end of the block 178 is arranged to enter between the spaced projections 216 upon the clutch box 212, and the block is formed with inclined faces 218 arranged to engage the clutch rolls 214 to force the rolls against 75 the rod 166 to lock the rod from forward movement relative to the clutch box. The clutch box carries oppositely projecting pins 220 and 222, of which the pin 220 is connected with the pin 198 by means of a spring 224, 80 and the pin 222 is connected by a spring 226 with a pin or bolt 228 secured in the cam lever 180, as shown in Fig. 5. The springs 224 and 226 tend to move the clutch box 212 forwardly relatively to the block 178, 85 and thus to keep the inclined faces 218 of the block in engagement with the clutch rolls 214. The block 178 is moved forwardly and rearwardly to cause the roll clutches to clutch and release the bar 166, and to move 90 the second roll clutch to retract the bar by the movement of the cam lever 180. The cam lever carries a cam roll 229 at the end of its upper arm which engages in a cam groove in a cam disk attached to the main 95 shaft 38 of the machine.

The parts are shown in the drawings in the positions which they assume when the back gage is locked in its forward or work engaging position. It will be noted that the clutch 100 rolls 208 are held against the rod 166 through the engagement of the inclined faces 210 on the block 178 with the rolls, thereby locking the rod against rearward movement, and that the clutch rolls 214 are held against the 105 rod through the engagement of the inclined faces 218 on the block with the rolls, thereby locking the rod against forward movement. As the lower arm of the cam lever swings rearwardly from the position shown in the 110 drawings, carrying the block 178 rearwardly therewith, the inclined faces 210 of the block are disengaged from the clutch rolls 208, allowing these rolls to release the bar 166, while the clutch rolls 214 are held in engagement with the bar, and the clutch box 212 and the bar 166 are moved rearwardly with the block. The retracting movement of the bar carries the back gage out of engagement 115 with the shoe. As the lower arm of the cam 120 lever 180 swings forwardly, carrying the block 178 forwardly therewith, the inclined faces 218 of the block are engaged by the clutch rolls 214, thereby locking the rod against forward movement, and the clutch box 212 is moved forwardly with the block 178. The forward movement of the clutch box 125 130

lever 180 swings forwardly, the clutch box 212 is held back during the first part of the forward movement of said arm, thereby causing the inclined faces 218 on the block 178 to disengage the clutch rolls 214, so that the clutch rolls are released from clutching engagement with the bar 166, allowing the bar to be advanced to carry the back gage into engagement with the shoe by the action 5 of the spring 194. Before the lower arm of the cam lever 180 has reached the limit of its forward movement, the clutch box 212 is released and allowed to be moved forward by the springs 224 and 226 until the clutch rolls 214 are again engaged with the inclined faces 218 of the block 178. The mechanism for thus holding back and releasing the clutch box comprises a latch lever 230 pivoted upon a stud 232 secured in a bracket 10 234 attached to the frame of the machine. The latch lever 230 is provided with spaced arms 236 embracing the rear end of the clutch box 212, and each having a catch projection 238 arranged to engage in front of 15 one of the lateral projections 240 on the opposite sides of the clutch box. The latch lever 230 is actuated in a direction to carry the catch projections 238 downwardly in front of the lateral projections 240 on the clutch box by the action of the spring 194, the out-turned end of the arm 242 of which is seated in a socket in the lever 230, somewhat below the axis of the lever, as shown in Fig. 3. To enable the lever 230 to be actuated 20 in a direction to lift the projections 238 from in front of the lateral projections 240 on the clutch box, and thus release the clutch box as the lower arm of the cam lever 180 swings forwardly, the lever 230 is formed with an arm 244 through the lower end of 25 which passes a rod 246 pivotally connected at 248 to an extension on the cam lever. A nut 250 is adjustably mounted upon the rod 246 to engage the rear side of the arm 244 of the lever 230, and actuate the latter lever to lift the projections 238 thereon from in front of the lateral projections 240 on the clutch box as the lower arm of the cam lever 180 swings forwardly. With this construction, as the lower arm of the cam lever 180 swings rearwardly, the longitudinal rearward movement of the rod 246 allows the lever 230 to be actuated by the spring 194 to depress the arms 236 of the lever. After 30 the lateral projections 240 on the clutch box have cleared the projections 238 on the arms 236 of the lever 230, the lever 230 is actuated by the spring 194 to carry the projections 238 in front of the projections 240. As the lower arm of the lever 180 swings forwardly, the clutch box is held back by the engagement of the projections 240 thereon with the projections 238 on the lever 230, and the block 178 moves forwardly independently 35 of the clutch box, disengaging the inclined faces 218 of the block from the clutch rolls 214. The clutch rolls are thus released from clutching engagement with the bar 166, allowing the bar to be advanced by the action of the spring 194. As the lower arm of the cam lever 180 continues to swing forwardly, the nut 250 engages the arm 244 of the lever 230, and actuates the latter lever to lift the projections 238 on the lever from in front of the lateral projections 240 on the clutch box, thereby releasing the clutch box. The springs 224 and 226 will then move the clutch box forwardly on the bar 166, carrying the clutch rolls 214 into engagement with the inclined faces 218 on the block 178. 40 The continued forward movement of the lower arm of the cam lever after this occurs carries the inclined faces 210 on the block 178 into engagement with the clutch rolls 208. When the lower arm of the cam lever reaches the limit of its forward movement, the bar 166 will therefore be locked in position against forward and rearward movements by the action of the two roll clutches. 45 The machine is provided with the usual back rest arranged to engage the shoe below the back gage to assist in holding the shoe in position during the sewing operation. In the drawings the back rest is indicated at 252, and is carried at the forward end of a slide 254 mounted to slide in suitable guides in the frame of the machine. The slide 254 is yieldingly pressed forwardly by means of a spring 256 coiled about a boss 258 formed on the frame of the machine, one arm of which engages a fixed abutment, and the other arm of which engages a pin 260 mounted on the slide 254. The forward movement of the slide 254 under the influence of the spring 256 is limited 50 by means of a stop lug or projection 262 formed on the frame of the machine, and extending into a slot 264 in the slide 254, the forward movement of the slide being limited by the engagement of the lug with the rear end of the slot. During the greater part of each cycle of operations of the machine, and preferably at all times except during the feeding movement of the shoe, the back rest is locked against forward movement, and is held against rearward movement, by the action of the spring 256. While the shoe is being fed the back rest is unlocked so that it can accommodate itself to the shoe. The locking of the back gage 55 against forward movement during the actuation of the channel guide to disengage its acting end from the bottom of the channel prevents the back rest from then moving forward and displacing the shoe. The mechanism for locking the back rest comprises a clutch roll 266 mounted between the upper face of the slide 254 and the inclined face 268 of a plate 270 secured to the frame above the slide. The parts are arranged so 60 65 70 75 80 85 90 95 100 105 110 115 120 125 130

that as the clutch roll 266 is forced forward between the plate 270 and the slide 254, it will wedge between the upper face of the slide and the inclined face 268 of the plate, and lock the slide from forward movement. The clutch roll is engaged by the head of a plunger 272 mounted in a suitable guide in the plate 270, and acted upon by a coiled spring 274 surrounding the body of the 10 plunger and interposed between the head thereof and the plate 270. By the action of the plunger 272 the roll 266 is normally forced forwardly into clutching position between the upper face of the slide 254 and the inclined face 268 of the plate 270, to lock the slide against forward movement. In order to unlock the slide 254, so that the back rest can accommodate itself to the shoe, an unlocking arm 276 is secured by the 20 screw 228 to the cam lever 180, and projects laterally therefrom through an opening in the frame into a position in front of the roll 266, as shown in Figs. 5, 6 and 8. As the lower arm of the cam lever 180 swings 25 rearwardly to retract the bar 166, the arm 276 engages the roll 266 and moves the same rearwardly against the tension of the spring 274 out of clutching position. The slide 254 is then free to move forwardly under the 30 action of the spring 256, or can be moved rearwardly against the tension of the spring. As the lower arm of the cam lever 180 swings forwardly, the arm 276 moves out of engagement with the roll 266, and the 35 roll is again moved forward by the action of the spring 274 on the plunger 272 into clutching position to lock the slide 254 from forward movement.

Having explained the nature and object 40 of the invention, and having specifically described a machine embodying the features of the invention in their preferred forms, what is claimed is:—

1. An inseam shoe sewing machine, having, in combination, stitch forming devices including a curved hook needle, a back gage, an endwise movable back gage controller bar, a clutch for locking the bar against rearward movement, a second clutch for 45 locking the bar against forward movement and for retracting the bar, and means for engaging the clutches to lock the bar and for actuating the latter clutch to retract the bar.

55 2. An inseam shoe sewing machine, having, in combination, stitch forming devices including a curved hook needle, a back gage, an endwise movable back gage controller bar, a bodily movable clutch for retracting the bar and for locking the bar, means for engaging the clutch and retracting the same to 50 retract the bar, for releasing the clutch to permit the bar to advance to carry the back gage into engagement with the shoe, and for re-engaging the clutch to lock the

bar when the back gage has engaged the shoe.

3. An inseam shoe sewing machine, having, in combination, stitch forming devices including a curved hook needle, a back gage, 70 an endwise movable back gage controller bar, a clutch for locking the bar against rearward movement, a clutch for locking the bar against forward movement and for retracting the bar mounted on the bar, a 75 clutch actuator mounted on the bar intermediate the clutches, means for moving the actuator to engage and release the first clutch to lock and unlock the bar, to move the second clutch to retract the bar, and to 80 disengage said second clutch to release the bar, and means for relatively moving the actuator and the second clutch to engage said clutch to lock the bar.

4. An inseam shoe sewing machine, having, in combination, stitch forming devices including a curved hook needle, a back gage, an endwise movable back gage controller bar, a clutch for locking the bar against rearward movement, a second clutch mounted 90 on the bar for locking the bar against forward movement and for retracting the bar, a clutch actuator mounted on the bar intermediate the clutches, means for moving the clutch actuator in one direction to disengage 95 the first clutch and to move the second clutch to retract the bar and in the opposite direction, to disengage the second clutch so as to permit the advance of the bar, and to engage the first clutch to lock the bar against 100 rearward movement, and means for moving the second clutch to engage the same and thereby lock the bar against forward movement.

5. An inseam shoe sewing machine, having, in combination, stitch forming devices including a curved hook needle, a back gage, an endwise movable back gage controller bar, a clutch for locking the bar against rearward movement, a second clutch for 110 locking the bar against forward movement and for retracting the bar, means for engaging the latter clutch and retracting the same to retract the bar, for releasing the same to permit the bar to advance to carry 115 the back gage into engagement with the shoe, and for engaging both clutches to lock the bar when the back gage has engaged the shoe.

6. An inseam shoe sewing machine, having, in combination, stitch forming devices including a curved hook needle, a back gage, an endwise movable back gage controller bar, a bodily movable clutch, and means for actuating the clutch to retract the bar and 120 to lock the bar in forward position against forward movement.

7. An inseam shoe sewing machine, having, in combination, stitch forming devices including a curved hook needle, a back gage, 130

an endwise movable back gage controller bar, a clutch for locking the bar against rearward movement, a clutch for locking the bar against forward movement and for retracting the bar, a common clutch actuator for the clutches arranged intermediate the clutches, and means for relatively moving the actuator and the clutches to engage and disengage the clutches, and for moving the actuator to move the second clutch to retract the bar.

8. An inseam shoe sewing machine, having, in combination, stitch forming devices including a curved hook needle, a back gage, a back rest, a one-direction roll clutch for locking the back rest against forward movement, a spring tending to move the back rest forwardly, and means for relatively actuating the parts of the clutch to unlock the back rest during each cycle of operations.

9. An inseam shoe sewing machine having, in combination, stitch forming devices including a curved hook needle, a back gage, an endwise movable back gage controller bar, a clutch for locking the bar against forward movement and for retracting the bar comprising a clutch box mounted on the bar and clutch rolls mounted in the box, a clutch actuator, means for moving the clutch actuator rearwardly to cause the clutch rolls to grip the bar and then to move the clutch to retract the bar and for then moving the actuator forwardly, means for holding the clutch

box in retracted position during the first part of the forward movement of the actuator to cause the clutch rolls to release the bar, a spring for advancing the bar upon its release by the clutch rolls, means for actuating said holding means to release the box, and a spring for advancing the box to reengage the clutch rolls with the actuator and cause the rolls to grip the bar.

10. An inseam shoe sewing machine having, in combination, stitch forming devices including a curved hook needle, a back gage, an endwise movable back gage controller bar, a clutch for locking the bar against forward movement and for retracting the bar comprising a clutch box mounted on the bar and clutch rolls mounted in the box, a clutch actuator, means for moving the actuator rearwardly to cause the clutch rolls to grip the bar and then to move the clutch to retract the bar and for then moving the actuator forwardly, a latch for holding the clutch box in retracted position during the first part of the forward movement of the actuator to cause the clutch rolls to release the bar, a spring for advancing the bar upon its release by the clutch rolls, means for throwing out the latch, and a spring for advancing the clutch box to reengage the clutch rolls with the actuator and cause the rolls to grip the bar.

WILLIAM C. MEYER.
